Fig. 3

Fig. 4

Fig. 5

Fig. 6

Fig. 7

Fig. 8

Fig. 1 is a front elevational view of a lathe showing my new design;

Fig. 2 is a top plan view thereof;

Fig. 3 is a rear elevational view;

Fig. 4 is an end view taken from the left in Fig. 1;

Fig. 5 is a transverse sectional view showing the headstock as viewed from the right in Fig. 1;

Fig. 6 is a sectional view showing the tailstock as viewed from the left in Fig. 1;

Fig. 7 is an elevational view of the tailstock taken from the right in Fig. 1; and

Fig. 8 is a perspective view of the lathe.

I claim:

The ornamental design for a lathe, substantially as shown.
